W. Hindhaugh,
Sir M. (B) (S)

UNITED STATES PATENT OFFICE.

WILLIAM HINDHAUGH, OF NEW YORK, N. Y.

IMPROVEMENT IN SAFETY-POCKETS.

Specification forming part of Letters Patent No. **56,049**, dated July 3, 1866.

To all whom it may concern:

Be it known that I, WILLIAM HINDHAUGH, of the city, county, and State of New York, have invented a new and Improved Safety-Pocket; and I do hereby declare that the following is a full, clear, and exact description of the same, which will enable others skilled in the art to make and use the same, reference being had to the accompanying drawings, forming part of this specification, in which—

Figure 1 represents a sectional front elevation of this invention. Fig. 2 is a transverse section of the same.

Similar letters of reference indicate like parts.

This invention consists in the arrangement of a spring-frame and sliding bolt, in combination with the mouth of a pocket, in such a manner that by compressing the spring-frame and pushing down the bolt the mouth of the pocket is securely locked, and by raising the bolt the mouth of the pocket opens spontaneously, and that by these means a simple and cheap attachment is obtained, which forms a perfect safeguard against pickpockets.

A represents a pocket, in the mouth of which is secured a metal frame, B. This frame is composed of two elastic springs of sheet-steel or other suitable material, which are united in such a manner that the same, when allowed to follow their inherent elasticity, spring open and give free access to the interior of the pocket.

From the inner strip of the frame B rises a plate, C, on which slides a bolt, D, which is guided by suitable staples *a*, secured in the plate C, and said bolt is made to move up or

down by a handle, *b*, which extends through the plate C and through the cloth of the vest or other garment in which the frame B is secured.

When the bolt is pushed down its head can be made to enter a loop or staple, *c*, which is secured to the inner surface of the outer strip of the spring-frame B, and by these means such frame can be closed and the mouth of the pocket A safely locked, so that no access can be had to the same until the bolt D is raised.

By raising the bolt the spring-frame is permitted to open and free access can be had to the interior of the pocket. This frame can be readily attached to watch-pockets in vests or to pockets of any other description. It is light and entirely concealed in the interior of the garment, and no part of the whole attachment is visible except the handle of the bolt D, which is so small that it can hardly be noticed, and by locking the spring-frame the contents of the pocket are perfectly protected against pickpockets.

Having thus described my invention, what I claim as new, and desire to secure by Letters Patent, is—

The bolt D and spring-frame B, in combination with the mouth of a pocket, constructed and operating substantially as and for the purpose described.

The above specification of my invention signed by me this 17th day of April, 1866.

WM. HINDHAUGH.
